(57) **CLAIM**

The ornamental design for a shower caddy, as shown and described.

DESCRIPTION

FIG. 1 is a perspective view of a shower caddy embodying the principles of the present invention;

FIG. 2 is a front view of the shower caddy seen in FIG. 1; FIG. 3 is a back view of the shower caddy seen in FIG. 1. FIG. 4 is a right side view of the shower caddy seen in FIG. 1, the left side view being a mirror image thereof;

FIG. 5 is a top view of the shower caddy seen in FIG. 1; FIG. 6 is a bottom side view of the shower caddy seen in FIG. 1; and,

FIG. 7 is a longitudinal sectional view of the shower caddy taken along line 7-7 in FIG. 2.

In the drawings, the broken lines depict environmental subject matter only and form no part of the claimed design. Shade lines having a combination of long and short lines in the drawings show contour and not surface ornamentation.
